DESIGN FOR A COLD CHISEL

Edwin A. Bardwell, Shelburne Falls, Mass., assignor to H. H. Mayhew Company, Shelburne Falls, Mass., a corporation of Massachusetts

Application April 3, 1934, Serial No. 51,304

Term of patent 14 years

To all whom it may concern:

Be it known that I, EDWIN A. BARDWELL, a citizen of the United States of America, residing at Shelburne Falls, in the county of Franklin and State of Massachusetts, have invented a new, original, and ornamental Design for Cold Chisels, of which the following is a specification, reference being had to the accompanying drawing, forming a part thereof.

Fig. 1 is a plan view of a cold chisel, showing my new design.

Fig. 2 is a side, elevational view of Fig. 1, and

Fig. 3 is a sectional view on the line 3—3 of Fig. 1, showing the embossing in section.

I claim:

The ornamental design for a cold chisel, as shown and described.

EDWIN A. BARDWELL.
